CLAIM

The ornamental design of a misting device as shown and described.

DESCRIPTION

FIG. 1 is a top isometric view of a misting device illustrating the new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top planar view thereof;

FIG. 7 is a bottom planar view thereof; and,

FIG. 8 is a bottom isometric view thereof.

The dot-dash broken line shows the bounds of the claim and the broken lines in the drawing views represent portions of the misting device that form no part of the claimed design.
